ASH TRAY

William A. Rosenberger, Hagerstown, Md.

Application April 23, 1940, Serial No. 331,247

4 Claims. (Cl. 131—240)

The present invention relates to ash trays for receiving cigar and cigarette ashes and temporarily supporting cigars and cigarettes while smoking. More particularly, the present invention relates to a novel ash tray structure for safely supporting a lighted cigar or cigarette to prevent damage resulting from accidental dislodgement of the cigar or cigarette and to support them in such a manner that their unlighted ends will remain sanitary and clean.

The ash trays now on the market are provided with curved depressions or formations of other suitable character for receiving and supporting burning cigars or cigarettes. These supports engage the cigar or cigarette intermediate its ends and are usually placed on the peripheral rim of the ash receiver. As a consequence, a cigar or cigarette balanced on the support overhangs the support at both ends and, if permitted to continue burning, the overhanging weight of the unlighted end will in the course of time cause the cigar or cigarette to fall upon the table top or cover upon which the ash receiver is placed and burn the table, or table cover, and in some instances start serious fires. If, on the other hand, the cigar or cigarette is placed with its burning end in the ash tray and the unlighted end against the peripheral wall, the cigar or cigarette may roll into the ash receiving bowl and be covered with ashes or the portion engaging the smoker's lips may contact an area on the peripheral wall where cold or other germs have collected from the cigars or cigarettes of other smokers.

It is, therefore, the primary object of the present invention to provide a safety ash tray adapted to eliminate the sources of disease and damage prevalent in present commercial ash receptacles.

Another important object of this invention is to provide an ash receiver with a supporting device which will prevent a cigar or cigarette from falling onto the supporting table or table cover when it is forgotten and allowed to continue burning.

It is a further object of this invention to provide an ash tray with a support adapted to temporarily support a cigar or cigarette while it is being smoked and positively prevent its dislodgement from the ash tray if inadvertently left burning.

It is another object of this invention to provide an ash tray designed to assure retention of a burning cigarette until it has been completely consumed.

It is a further object of this invention to provide an ash tray with a support capable of supporting a cigar or cigarette within the confines of an ash tray yet out of contact with the ashes.

Another object of the present invention is to provide an ash tray for supporting a cigar or cigarette in such a manner that the lip engaging portions are maintained out of contact with contaminated surfaces.

It is a further object of the present invention to provide an ash tray of simple construction capable of preventing damage caused by forgotten cigarettes.

Other objects will appear from the appended claims and following description read in conjunction with the attached drawings wherein:

Figure 1 is a plan view of an ash receiver embodying one form of the present invention.

Figure 2 is a fragmental sectional view taken along lines 2—2 of Figure 1 and illustrating the manner of placing the cigarette in the support.

Figure 3 is a fragmental sectional view looking into the end of the support of Figures 1 and 2.

Figure 4 is a fragmental sectional view, illustrating a modified form of the present invention.

Figure 5 is a fragmental plan view of the modification shown in Figure 4.

Figure 6 is a fragmental sectional view of an ash tray like that of Figures 4 and 5 but made in two parts.

Figure 7 is a plan view of a further modified form of the present invention.

Figure 8 is a sectional view taken on lines 8—8 of Figure 7.

Figure 9 is a plan view illustrating a sheet metal ash tray embodying the form of Figures 7 and 8.

Figure 10 is an end view of the sheet metal ash tray shown in Figure 9.

Figure 11 is a sectional view taken on lines 11—11 of Figure 9.

Figure 12 is a perspective view of a fragment of the cigarette supporting member of Figures 9, 10 and 11.

Figure 13 is a fragmental sectional view showing a different manner of attaching the member of Figure 12 to the ash receptacle of Figures 9 to 11, and

Figure 14 is a fragmental sectional view of a modified form of support, wherein the support is inclined.

With continued reference to the drawings wherein like reference characters are utilized throughout the several figures of the drawings to designate the same part, numeral 15 design-

nates generally an ash tray embodying the present invention.

Ash tray 15 preferably consists of a pressed or die cast metal ash receiving bowl or receptacle 16 having an upstanding peripheral wall 17. Wall 17 at one or more points along the upper edge is provided with metal shelves or cigarette supports 18. In this form of the invention, support 18 is of generally circulate form in cross-section and is illustrated as a separate member secured in any suitable manner, such as spot welding, in a notch 19 formed in the upper edge of wall 17. Support 18 at its outermost end is closed by wall 21 and is provided with an overhanging rim 22. The side walls of support 18 are notched at 23 to enable a cigarette to be grasped so as to place it in position on the support and remove it as desired. The free ends of the side walls are bent outwardly at 24 to provide a flared mouth to guide the cigarette into the support 18 and eliminate any sharp edges which might tear the cigarette.

While the form of invention shown in Figures 1 to 3 is described as a metal ash tray with a separately attached support, it is to be understood that any suitable material such as glass, porcelain, plastics, etc., may be used and that supports 18 may be integrally formed on wall 17.

In use, a cigarette is placed on support 18 in position "A" and pushed in the direction of the arrow to position "B" until the unlighted end contacts wall 21 and is received in rim 22. The lighted end, of course, overhangs the opposite end of support 18 as shown in Figures 1 and 2.

Rim 22 and wall 21, however, engage the unlighted end of the cigarette and prevent the weight of this overhanging portion from tilting the cigarette into the ash tray and limit the longitudinal movement of the cigarette and position it so that it cannot accidentally be dislodged from the ash tray and fall upon the table, table cover, floor or rug and damage them or start a destructive fire.

A modified form of the invention is illustrated in Figures 4 and 5 wherein the same reference characters are used to designate the same parts. A molded ash tray 15a made from glass, porcelain, synthetic plastic or the like is illustrated. In this modification, the cigarette is supported by a saddle or support 28a carried by a pair of spaced ribs or webs 29 formed on the upstanding wall 17. The ribs and saddle are preferably of such length that the distance "C" is slightly in excess of one-half the length of a cigarette so as to prevent tilting of a new cigarette into the ash tray. Support 28a is provided with an upwardly facing groove 31 designed to receive a portion of the body of the cigarette and prevent it from rolling off the support. Groove 31, as clearly shown in Figure 4, is spaced a slight distance above the upper surface of ribs 29 so that the cigarette rests on support 28a with its lighted end overhanging the ash receiver and the unlighted end overhanging the space or slot 32 between ribs 29. In order to prevent the overhanging weight of the unlighted end of a partially burned cigarette from dislodging the cigarette, it is positioned in groove 31 with its unlighted end in contact with a small knob or protuberance 33, preferably of conical form, formed on wall 17 adjacent its upper edge. Protuberance 33 is centered with respect to groove 31 and is disposed in horizontal alignment with the center line of the cigarette.

In use with the cigarette in groove 31 with its 75

unlighted end in contact with protuberance 33, the cigarette is in effect suspended between saddle 28a and protuberance 33.

Referring to Figure 4, it will be noted that protuberance 33 contacts the tobacco at the end of the cigarette and that the portion of the end engaging the smoker's lips does not contact any surface which may contain ashes or germs. As a consequence, the present modification provides 10 a sanitary ash tray of extreme hygienic appeal. Furthermore, this hygienic feature is equally applicable to the support of cigars by suitable alterations of the dimensions of the saddle and the protuberance.

In the event that a lighted cigarette is left upon support 28a, it will burn until the lighted end burns past end 34 of saddle 28a. When this occurs, the cigarette will drop through slot 32 into the ash receiving bowl and burn itself out where no damage can be done.

If desired, the ash tray of Figures 4 and 5 may be made in two parts as shown in Figure 6. In lieu of spaced ribs 29, the wall 17 of this ash tray 15b is provided with an inwardly extending annular rim 35. The inner periphery of rim 35, on its underside, is provided with an annular flange 36 designed to receive a ring-shaped element 37 carrying saddles 28b. To this end, element 37 is provided with an annular flange 38 which cooperates with flange 36 to removably support element 37 within the confines of wall 17. At suitable points around rim 37, short inwardly extending ribs or webs 39 are provided for supporting saddles 28b.

As clearly shown in Figure 6, the groove 31, knob 33, rim 37 and ribs 39 bear the same relation one to the other, as pointed out in connection with Figures 4 and 5. The cigarette, therefore, is supported in a sanitary manner. The principal advantage of this form of the invention lies in the ability to remove element 37 and the integral saddles 28b so that the bowl 16 may be readily cleaned, particularly at points beneath ribs 39 and saddles 28b. In lieu of slots 32, the upper surfaces of rim 35, element 37 and ribs 39 may be curved or slightly inclined so that the burning stub of a cigarette will fall into bowl 16 when the cigarette burns beyond end 34 of saddle 28b.

A further modification of this invention is shown in Figures 7 and 8. In this form of the invention, ash tray 15c comprises an ash receiving bowl or receptacle 41 formed of a molded plastic material or die cast metal. Bowl 41 is provided with an upstanding peripheral wall 42 having wide notches 43 designed to support a cigar as shown in Figure 7. The upper edge of wall 42 is of insufficient width to support a cigar or cigarette so that they must be inclined into the ash tray in the event that a smoker inadvertently or through perversity fails to utilize the sanitary supports provided by this invention. This feature definitely preserves the fire or burn prevention features of this invention, even though a user fails to avail himself of the sanitary supports provided. In this connection, it should be understood that a cigar will not continue to burn after it is laid aside but will promptly go out so that when it is placed in the ash tray as shown in Figure 7 there is no danger of it burning down and falling from the ash tray.

The bottom 44 of bowl 41 is provided with one or more hollow upwardly extending tapered posts, or saddles 45, the upper surface of which is provided with a groove 46 for receiving a

cigarette. In alignment with groove 46, and extending outwardly from each end thereof, is an outwardly tapering shelf or wing 47. The upper surfaces of shelves 47 are in the plane of the bottom of groove 46 and cooperate therewith to support a cigarette.

Wall 42 at suitable points adjacent its upper end and in alignment with the longitudinal center line of a cigarette reposing in groove 46 is provided with conical knobs 33. Knobs 33, as shown in Figures 7 and 8, are provided opposite each end of groove 46 and the distance between knobs 33 and the adjacent end of groove 46 slightly exceeds the distance between similar points of the ash trays of Figures 4 to 6. This difference in spacing is due to the location of posts 45 at the center of bowl 41 and makes it necessary to utilize shelves 47 so as to prevent burning cigarettes from falling into the ash tray until they are too short for further smoking.

The centered relation of posts 45 and the oppositely disposed knobs 33 make it possible to use the cigarette holder from either side while obtaining the desired sanitary and supporting features of this invention.

Figures 9 to 13 illustrate the application of the double ended saddle feature of Figures 7 and 8 to a sheet metal ash tray. In these figures, ash tray 15d is illustrated as rectangular in shape and is formed of relatively thin sheet metal by suitable die presses. Preferably the bowl 41a is formed from a single piece of sheet metal, the spaced knobs or protuberances 33 being pressed in the longitudinal walls and the notches 48 being cut during the single forming operation.

As clearly shown in Figure 11, the end walls 49 between notches 48 are provided with extensions or tabs 51. Tabs 51 are provided for securing a suspended cigarette supporting member 52 between walls 49 in a manner to be presently pointed out.

Member 52 comprises a single sheet metal stamping providing spaced cigarette saddles 45a and grooves 46a. Member 52 is also provided with shelves 47a provided by the edges of upstanding walls 53 formed by suitably creasing and folding the sheet metal blank along the vertical centerline of grooves 46a during the stamping operation. Member 52 at its opposite ends is provided with an upstanding flange 54. The length of member 52 between flanges 54 is such that a tight fit results when it is placed within bowl 41a with flanges 54 in engagement with the inner surface of walls 49. To further secure member 52 in place, tabs 51 are spun around the edge of flange 54 into tight engagement with the inner faces of flanges 54.

Referring to Figures 9 and 10, it will be seen that shelves 47a and the ends of cigarettes resting in grooves 46a overlie longitudinally extending spaces 55 formed between the side walls of bowl 41a and the edges of member 52. It will also be clear that notches 48 are in alignment with these spaces. Due to this construction, the cigarette may readily be grasped by the smoker in placing it on or removing it from grooves 46a. Furthermore, member 52 is located at a predetermined level so that the center line of cigarettes reposing in grooves 46a will coincide with the major axis of knobs 33 to secure the sanitary advantages of this invention.

If desired, member 52 may be designed for ready removal for purposes of cleaning ash tray 15d. To accomplish this end, end walls 49 of bowl 41a are formed without tabs 51 as clearly

shown in Figure 13 and a slightly longer member 52a provided with a downwardly extending flange 54a is substituted for member 52. Flange 54a is designed to lap the outer face of walls 49 and fit snugly enough to prevent accidental disassembly of the two parts.

From a consideration of Figures 1 through 13 of the drawings, it will be seen that the various forms of the invention require some slight degree of care on the part of the smoker in order to obtain the desired sanitary benefits. However, it should also be noted that the fire or damage preventing features of this invention are obtained irrespective of the personal carelessness of the smoker. To remove this possible failure to gain the full benefits of this invention, the saddles 28a, 28b, 45 or 45a may be drastically inclined with respect to a horizontal plane to cause a cigar or cigarette to automatically gravitate into the desired position.

Such a structure is shown in Figure 14 of the drawings wherein an ash tray 15e like that of Figures 7 and 8 is illustrated. In this construction, post or saddle 45b is higher at its left end than at the right end and a shelf 47a is provided at the lowermost end to prevent the cigarette from dropping into the bowl it has been substantially burned out. Furthermore, knobs 33a similar to knobs 33 are formed nearer to the bottom of wall 42 and are inclined so that their principal axis coincides with the center line of a cigarette reposing in groove 46b. While the inclined saddle does not permit the use of the saddle from either side, oppositely inclined saddles may be formed adjacent saddle 45b to obtain this result.

In using this form of the invention, the cigarette is placed in groove 46b with the unlighted end facing downwardly. If the unlighted end is not placed in contact with knob 33a, the cigarette, due to its own weight, will slide along groove 46b until the end contacts knob 33.

In the preceding description, the applicability of this invention to cigarettes has been emphasized since it is well known that a cigarette will continue burning until consumed while a cigar will go out. The danger of damage from a forgotten cigarette is, accordingly, greater. This invention, however, by appropriate changes in proportions of the parts is equally capable of use with cigars and the specification and claims wherever the word "cigarette" is used is intended to include "cigars."

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A safety ash tray comprising an ash receiving bowl, a supporting member carried by said bowl and engaging a portion of a cigarette intermediate its ends, said supporting member comprising at least one saddle disposed within the confines of said bowl in spaced relation to the bottom of said bowl and having a substantially U-shaped groove for receiving said cigarette and means comprising a protuberance formed

on the inside of said bowl and disposed substantially coaxially with said member and in substantial alignment with the longitudinal center line of a cigarette lying in said groove for contacting the unlighted end of said cigarette and cooperating with said member to removably support said cigarette with said end out of contact with the ashes in said bowl and tending to prevent its accidental dislodgment.

2. A safety ash tray comprising a bowl shaped ash receiver, means for supporting a cigarette intermediate its ends and means contacting the unlighted end of said cigarette at a point inwardly of its peripheral lip engaging portions whereby said lip engaging portions are maintained out of contact with contaminated surfaces likely to contain foreign matter or germs.

3. The combination defined in claim 2 wherein both of said means are within the confines of said bowl whereby the possibility of the cigar-

ette being dislodged from its support and damaging the surface supporting said ash tray or starting a fire is eliminated.

4. An ash tray comprising an ash receiving bowl, means inclined at a substantial angle to a horizontal plane for engaging said cigarette intermediate its ends to retain said cigarette in an inclined position with its unlighted end lowermost and permit said cigarette to slide downwardly along said means and means disposed in alignment with said first mentioned means for engaging the unlighted end and arresting its sliding motion, both of said means being within the confines of said bowl and said last mentioned means being disposed at a substantial distance above the bottom of said bowl to prevent contact of the unlighted end with the ashes in said bowl.

WILLIAM A. ROSENBERGER.
